(57) **CLAIM**

The ornamental design for a water filtration container, as shown and described.

DESCRIPTION

FIG. 1 is a top perspective view of a water filtration container with the lid spout in open position showing my new design;

FIG. 2 is a side view thereof with the lid spout removed for ease of illustration;

FIG. 3 is a top plan view thereof;

FIG. 4 is a bottom plan view thereof;

FIG. 5 is a front view thereof;

FIG. 6 is a rear view thereof; and,

FIG. 7 is a top plan view thereof with the lid removed for ease of illustration.
